(57) **CLAIM**

I claim the ornamental design for a hunting camera, as shown and described.

DESCRIPTION

FIG. 1 is a front and right side perspective view of a hunting camera showing my new design;

FIG. 2 is a front and left side perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the hunting camera in which the design is embodied that form no part of the claimed design.
